UNITED STATES PATENT OFFICE.

WLADYSLAW WAGNER, OF LODZ, POLAND.

CUPOLA-FURNACE.

1,208,416.

Specification of Letters Patent. Patented Dec. 12, 1916.

Application filed February 17, 1913. Serial No. 749,016.

To all whom it may concern:

Be it known that I, WLADYSLAW WAGNER, a subject of the Czar of Russia, and residing at Lodz, Russian Poland, have invented 5 certain new and useful Improvements in Cupola-Furnaces, of which the following is a specification.

My invention relates to cupola furnaces, and a primary object is to provide a furnace 10 which will serve not only for smelting the usual charge-iron, but also in an exceedingly economical manner for smelting simultaneously iron shavings. To this end I provide in the smelting zone of the cupola 15 furnace an adjoining conduit, into which the iron shavings are supplied from above and therefore directly into the smelting zone, these shavings being preferably pressed into briquets by suitable devices, 20 and which is so connected below to a receiver that the shavings supplied become melted by the surplus heat obtained when melting the usual charge-iron, and hence 25 without use of additional combustion material and with the smallest possible waste. Moreover these shavings when in the liquid condition reach the receiver without being exposed to the gases generated in the cupola furnace proper, *e. g.* sulfur, which is there 30 liberated during the smelting process. Moreover arrangements are made in the cupola furnace for automatically mixing the shaving-iron and charge-iron together when such is desired.

One illustrative embodiment of my invention is represented by way of example in the accompanying drawing, wherein:—

Figure 1 is a sectional elevation of the new cupola furnace, Fig. 2 a section on the line 40 A—A in Fig. 1, Fig. 3 a section through a portion of the press for the shavings, Fig. 4 an elevation of the portion referred to in Fig. 3, Fig. 5 a section through one of the conical nozzles in the briquet-making device, and Fig. 6 an end view of said nozzle.

Referring to the drawing, the cupola furnace *a*, which is otherwise constructed in the usual manner, has a fore-hearth or container *b* for the molten charge-iron. According to 50 my invention a conduit *c* is built in the melting zone of the cupola furnace, and is connected below with a receiver *d*. In the upper part of the conduit *c*, a device is arranged for supplying to the conduit the 55 shavings to be melted, such shavings being preferably supplied in a compressed condi-

tion. The compression device, which can be variously arranged, preferably consists of two cylinders *e*, *f* which are suitably bolted together and rest on a bracket *g*. Connected to the cylinders are tubes *h*, through which the shavings pass from the charging platform into the cylinders. A piston *i* moves in each cylinder, being reciprocated by a suitable crank-drive *k*. Extending 60 from each cylinder is a tapered nozzle *l* which is offset from the wall of said conduit *c* and is directed toward the latter. When therefore the shavings pass through the tubes *h* into the cylinders *e*, *f*, they are 65 thrust forward by the reciprocating pistons *i*, and, owing to the resistance produced by the narrowing taper of the nozzle *l*, become compressed, to be thereafter thrust forward into the conduit *c*. Here the shavings are 70 immediately converted to molten iron by the surplus heat, and an extremely small waste thus occurs. The molten shavings fall through the conduit *c* in the receiver *d*, and can be here reduced in clean condition. Now 75 to automatically obtain a predetermined mixture of shaving-iron with the usual charge-iron, or to prevent such mixture, the bottom *m* of the cupola furnace proper is 80 constructed in a suitable manner. For instance when it is desired to prevent a mixture 85 of the shaving-iron with the charge-iron, the bottom has a surface inclined toward the usual container *b*, so that, owing to this inclined plane, all the charge-iron is 90 conducted away toward the hearth *b* and does not reach the hearth *d*. If however a predetermined mixture of charge-iron and shaving-iron is desired, the bottom, as seen 95 in Fig. 1, is formed of two inclined surfaces meeting at an obtuse angle, the length of such surfaces being in each case variously determined according to the percentage of the mixture to be obtained. This is indicated by the various steps 0 to 5. As is 100 readily understood, owing to this arrangement of surfaces, a portion of the charge-iron flows into the container *d*, the amount of such iron being directly proportional to the length of the surface adjacent to and 105 leading toward the container *d*. A predetermined mixture of charge-iron and shaving-iron is thus automatically obtainable, while only the pure charge-iron is found in the container *d*. When a very large quantity of 110 shaving-iron collects in the container *d* and is not tapped therefrom, a portion of this

iron will overflow into the container *b*, whereby a mixture of charge-iron and shav-
ing-iron can be here obtained.

It is evident from the above that by my
5 novel construction of cupola furnace it is
possible to smelt shavings in the most eco-
nomical manner, without the use of addi-
tional combustion material and without
10 waste, only the surplus heat obtained when
smelting the ordinary charge-iron being now
needed for this purpose.

An advantage simultaneously obtained
15 with my new cupola furnace is that the
shavings, by being led direct into the smelt-
ing zone, are not exposed to the gases liber-
ated in the cupola furnace proper during the
smelting process, whereby these gases can
have no detrimental effect on the shaving-
iron.

20 I claim:—

1. In a smelting furnace, the combination
of a conduit associated with said furnace
and located within the smelting zone of the
25 latter, a receiver communicating with the
conduit from which the iron may be drawn
off, and means for pressing iron shavings
into briquets connected with the conduit at
a point adjacent the smelting zone thereof
30 for introducing the iron shavings aforesaid
into the conduit.

2. A cupola furnace having a conduit lo-
cated within the smelting zone of the fur-
nace and provided with a fore-hearth or con-
tainer for charge iron, the bottom of the fur-
35 nace being inclined toward said container
for the purpose set forth.

3. A cupola furnace having a conduit lo-
cated within the smelting zone of the fur-

nace and provided with a fore-hearth or con-
tainer for charge iron, the bottom of said 40
furnace being formed with oppositely in-
clined surfaces meeting at an obtuse angle,
one of the surfaces inclining toward the
container for the charge iron, a receiver com-
municating with said conduit, means for 45
compressing and introducing iron shavings
into the conduit so that they will be depos-
ited in said receiver, the other surface of the
bottom of the furnace inclining toward said
receiver. 50

4. A cupola furnace comprising a bottom
having oppositely inclined surfaces, and hav-
ing a conduit located within the smelting
zone of the furnace, a container disposed at
one side of the furnace and adapted to 55
receive charge iron, one of the inclined bot-
tom surfaces of the furnace inclining to-
ward said container, a receiver communicat-
ing with the conduit aforesaid and disposed
at the side of the furnace opposite the said 60
container, the other surface of the bottom
of the furnace inclining toward said re-
ceiver, the arrangement of the bottom sur-
faces aforesaid being such that charge iron
introduced into the furnace is directed to 65
the container above referred to, and iron
shavings introduced into the conduit are di-
rected to the receiver.

In testimony, that I claim the foregoing
as my invention, I have signed my name in
presence of two subscribing witnesses. 70

WLADYSLAW WAGNER.
